UNITED STATES PATENT OFFICE.

JOSEPH A. MEYER, OF NEWARK, NEW JERSEY.

LEATHER-SPLITTING MACHINE.

1,410,703.

Specification of Letters Patent. Patented Mar. 28, 1922.

Application filed October 9, 1919. Serial No. 329,420.

To all whom it may concern:

Be it known that I, JOSEPH A. MEYER, a citizen of the United States, and a resident of Newark, in the county of Essex and State 5 of New Jersey, have invented new and useful Improvements in Leather-Splitting Machines, of which the following is a specification.

This invention relates especially to the 10 ring roll of a leather-splitting machine, and more particularly to the means for driving the rings of said roll and engaging the same with the leather.

The objects of the invention are to secure 15 an improved construction for driving the rings of the ring roll from the shaft on which they are arranged, so as to leave them free to move radially against the resiliency of the rubber roll and accommodate variations of thickness in the leather; to arrange 20 between successive rings means for frictionally transmitting rotation from one to another, and to place at the outer ends of the series of rings means positively driven by 25 the shaft and adapted to drive the rings frictionally; to provide for this purpose collars fast upon the shaft, and to transmit rotation from said collars to the adjacent rings and from one ring to another by means 30 of interposed resilient members which exert pressure oppositely upon the two members between which they are placed; to provide an improved friction ring for this purpose; to provide the ring roll with 35 means oppositely arranged at opposite ends of the roll and tending to separate the lateral marginal portions of the hide as it passes through the machine; to thus enable the gage roll to be smooth, and 40 avoid any impressions or markings on the upper or grain side of the leather which said gage roll engages; to provide upon the ring roll, which engages the under or inner side of the leather which is hidden 45 in use the means for exerting upon the leather a tendency to move it longitudinally of the rolls, and thus locate where they will do no harm the impressions or markings made thereby upon the leather; to insure 50 that when the outer edges of the hide are retarded by pulling backward upon them, as is necessary in the splitting operation, the hide does not have to drag over the means for stretching or spreading the leather laterally, since those rings which engage the 55 portions of leather being retarded can

change their rotary speed accordingly; to thus secure a stretching or spreading effect upon the hide which is automatically adjustable to the speed of travel of different 60 portions of the hide; to effect a more perfect stretching or spreading action, with a less liability of injury, and thus obtain a better and more finished product, and to obtain other advantages and results as may be 65 brought out in the following description.

Referring to the accompanying drawings, in which like numerals of reference indicate the same parts throughout the several views,

Figure 1 is a transverse vertical sectional 70 view through a portion of a splitting machine embodying a ring roll constructed in accordance with my invention;

Figure 2 is an enlarged side elevation thereof, portions being omitted for clearness in illustration;

Figure 3 is a top plan view of the ring roll and rubber roller taken on the line 3—3 of Fig. 2;

Figure 4 is a diagrammatic sectional view 80 showing the manner of displacement of the ring roll sections by irregularities in the hide;

Figure 5 is a longitudinal sectional view through the ring roll at one end thereof; 85

Figure 6 is a detail perspective view of one of the ring roll sections or rings; and

Figure 7 is a similar view of one of the spring friction rings.

Specifically describing the present embodiment of the invention, the numeral 1 designates the frame of a conventional leather splitting machine upon which a table or bed 2 is mounted to support the leather 3 to be split as it is fed to the splitting devices. 95 Above the table 2 and longitudinally of the machine is mounted the gage roll 3 adjustable by conventional means 4, and below the gage roll and parallel thereto is mounted my improved ring roll 5, the leather to be split 100 passing between the gage roll 3 and ring roll 5 to the usual band knife 6, and being split in the conventional manner into the two pieces *a* and *b*. The gage roll 3 is adjustable relatively to the ring roll 5 to accommodate 105 hides of various thicknesses, and the ring roll 110 is held yieldingly in engagement with the under side of the hide by the rubber roll 7 which has frictional contact with said ring roll. The rubber roll is adjustable to vary the pressure of the ring roll 5 on the hide by means of levers 8 in which the rubber roll

is journaled, said levers being pivotally mounted on the frame of the machine, as at 9, and operated by a rod 10 engaging an eccentric 11 on a rock shaft 12 mounted in the 5 machine frame. A handle 13 is connected to the rock shaft 12 for oscillating the same, and a clamping screw 14 carried by the handle 13 engages a segmental slot 15 in a bracket 16 and enables the handle to be 10 clamped to the bracket to hold the rubber roll in an adjusted position.

It is a feature of my invention to provide positive drive means for the ring roll in addition to the friction drive thereof provided by the rubber roll, and to so construct the ring roll that the two end rings of the roll are frictionally driven directly from the ring roll shaft while the other rings are frictionally driven from the end rings and each 20 other, at the same time providing for relative slipping and radial movement of the individual rings upon the ring roll shaft to accommodate various speeds of travel of different portions of the hide and irregularities 25 in the surface of the hide. For these purposes the ring roll is shown as comprising a shaft 17, below and parallel to the gage roll 3, and a plurality of similarly formed rings 18 mounted side by side on the shaft between 30 a pair of stop collars 19 and 20 fixed to the shaft near the ends thereof, in any suitable manner, as by the pins 21, so as to form in effect a continuous solid roll. The rings extending from the center of the shaft to the 35 stop collars are respectively provided with oppositely extending spiral grooves 23 and 24, the rings between the center of the shaft and one stop collar having left-hand spiral grooves, and the rings between the center of 40 the shaft and the other stop collar having right-hand spiral grooves. All of the rings 18 are otherwise identical in construction, being of the same diameter and each ring being formed with a central opening 22 sufficiently 45 larger than the shaft 17 in diameter to allow the rings to move radially of the shaft to accommodate the passage of the largest irregularity or projection ordinarily on a hide. In one side face of each ring 18 is formed an annular recess 25 of a size and 50 depth sufficient to receive a friction spring ring 26 so that when the ring is not under compression it will slightly project out of the recess shown by Figure 5 of the drawings. One of these friction rings is provided in each of the rings 18, and comprises a ring 55 of resilient metal formed with an annular groove 27 to provide two substantially flat and spaced parallel side portions 28. One 60 of the stop collars, in the present instance the collar 19, is preferably also formed with an annular recess 31 to receive one of the friction rings 26, similarly to the rings 18.

In assembling the rings 18 upon the ring 65 roll shaft a friction ring 26 is inserted in the

annular recess 25 of each ring 18 and in the recess 31 of the stop collar 19. One of the stop collars is then fixed upon the shaft 17 and the rings 18 slid upon the shaft in the manner shown by Figures 3, 4 and 5 with a 70 friction ring 26 interposed between each two rings 18. The other stop collar is then slipped on the shaft and forced toward the fixed stop collar to compress the spring friction rings 26 and force the rings 18 close 75 together. This action is continued until there is just sufficient clearance left between the various rings 18 to allow them to individually slip radially when pressed upon by an irregularity in the hide passing between 80 the gage roll and ring roll, after which the last stop collar is pinned to the shaft, thus locking the rings 18 against longitudinal movement upon the shaft. This clearance is indicated by heavy lines between the rings 85 18 in Figure 5 of the drawings.

When the ring roll is in position in the machine the peripheries of the rings thereof frictionally engage the periphery of the rubber roll which is driven in any suitable manner (not shown). The rings are thus individually and frictionally driven from the rubber roll, and are also frictionally driven by means of the stop collars 19, 20 and friction rings 26 from the ring roll shaft 17 95 which is positively driven from the rubber roll by means of suitable gearing, such as the gear 32 on the rubber roll shaft, idler gear 33 and gear 34 on the ring roll shaft.

In the operation of the device the rubber 100 roll, ring roll, and gage roll rotate in the direction indicated by the arrows, to feed the hide or leather A to the band knife 6. The rings of the ring roll are yieldingly held against the underside of the hide by 105 the rubber roll, and should a projection or irregularity in the hide, as indicated at c in Fig. 4, strike one of the rings, said ring will yield radially by virtue of its loose fit upon the ring roll shaft and press into the 110 rubber roll as shown by Fig. 4, the rubber roll causing the ring to assume its original position after the irregularity has passed. This displacement in no way affects the other 115 rings which continue to rotate freely. The displaced ring is always frictionally driven from the friction rings 26 of adjacent rings and also from the rubber roll. It often occurs that as a hide is being fed through the machine the skirts or marginal edges thereof 120 travel faster than the thicker middle portion which is harder to split, and the edges are pulled back or retarded by the operator. In the usual construction of ring roll this pulling is done against the positive drive of 125 the rings and the only retardation is caused by hard enough pulling to cause the hide to slip under the ring roll and gage roll. With my construction the friction spring rings allow the rings at the end of the shaft 130

- to be retarded and slip backwardly, at the same time allowing the other rings to rotate in the usual manner to feed the hide. This is much simpler, and reduces the strain on 5 the hide as well as the work incident to pulling back on the skirts of the hide. In the use of common ring rolls in splitting machines difficulty is encountered in preventing the rings from being tipped edge-wise by irregularities in the hide and causing ring marks or grooves in the leather. With my construction the flat sides and spring action of the spring rings 26 hold the rings 18 in an upright position and thus 10 prevent tilting of the rings and provide against ring marks on the hide. The stop collars 19 and 20 are preferably smaller in diameter than the rings 17 and not provided with spiral grooves so that they will not 15 engage the hide to interfere with the action of the rings 18. As the ring roll rings 18 rotate, the spiral grooves 23 and 24 therein smooth the hide and stretch it from the center toward the edges to prevent bagging or wrinkling 20 thereof, and as each ring is provided with the spiral grooves, this smoothing action takes place even at roughest places in the hide and when the rings are displaced. I thus obtain the dual advantages of a spirally grooved roll and independently rotatable rings. As has been explained, the rings 18 are driven from the shaft 17 through the stop collars 19 and 20 and friction spring rings 26, and the friction is 25 increased by the resistance of the hide to the stretching action by the spiral grooves 23 and 24 which forces the rings 18 closer together and exerts more pressure on the friction springs 25.
- 40 It will be understood that the hide or leather goes through the splitting machine with the grain side uppermost or toward the gage roll and the flesh side underneath or toward the ring roll, and that 45 it is highly important to keep the grain side of the leather from any marring or disfigurement, since it is the side which is outermost or exposed when the leather is used. The under or flesh side of the 50 leather is hidden in use, and does not require so much care in operating upon the leather. Heretofore the means for spreading the leather longitudinally of the rolls, in a splitting machine, has been located upon 55 the gage roll, and the tendency has been to mark or make impressions upon the grain side of the leather, especially in pulling back upon the lateral margins of the piece of leather to retard them as has been already 60 described, since when this is done the gage roll continues turning as a whole and must slip or drag over the retarded portions of the leather. It will be noted that by putting upon the ring roll said means for 65 spreading or stretching the leather laterally I insure that it engages the under or flesh side of the leather where markings or impressions do no harm, and further enable the gage roll to be smooth, thus avoiding any liability of marring or disfiguring the grain 70 side of the leather. I furthermore reduce, if not entirely eliminate, any markings or impressions upon the leather by reason of its being required to slip or drag over the spreading or stretching means on the roll, 75 since I locate said stretching or spreading means upon a sectional roll, the sections or rings of which can rotate at different speeds or some of them even stand still with respect to others. It will be seen that by this construction when the lateral marginal portions of the leather are retarded the rings engaging them are also retarded and there is no slip or drag between the leather and ring sections, and consequently no marking or mar- 80 ring of the surface of the leather, since the ring roll must be sectional, anyway, in order to accommodate unevenness in the hide. It is for this reason advantageous to transfer the stretching or spreading means from the 85 gage roll to the ring roll, as well as for the reason heretofore mentioned, in order to prevent any possible marring or impressions on the grain side of the leather.
- Obviously various detail modifications and 90 changes can be made in the construction of my ring roll without departing from the spirit and scope of the invention, and I do not desire to be understood as limiting myself except as required by the following 100 claims when construed in the light of the prior art.
- Having thus described the invention, what I claim is:
1. In a splitting machine, the combination 105 of a gage roll and a ring roll adapted to feed the material to be split, said ring roll having a plurality of ring sections capable of turning independently of each other and provided with means for exerting upon the 110 material a tendency to move it longitudinally of the roll, means for frictionally driving said ring sections, and a rubber roll engaging said ring roll.
  2. In a splitting machine, the combination 115 of a gage roll and a ring roll adapted to feed the material to be split, said ring roll comprising a plurality of ring sections capable of turning independently of each other and each having spiral grooves in its peripheral 120 surface, means for frictionally driving said ring sections one from another, and a rubber roll engaging said ring roll.
  3. In a splitting machine, the combination 125 of a gage roll and a ring roll adapted to feed the material to be split, said ring roll having a plurality of ring sections capable of turning independently of each other and provided with spirally disposed surface dis- 130 tortions adapted to exert upon the material

- a tendency to move it longitudinally of the roll, and means for frictionally driving said ring sections.
4. In a splitting machine, the combination of a gage roll and a ring roll adapted to feed the material to be split, said ring roll comprising a plurality of ring sections capable of yielding transversely of the ring roll independent of each other and each having spiral grooves in its peripheral surface, means for frictionally driving said ring sections one from another, and a rubber roll engaging said ring roll.
5. In a splitting machine, the combination of a gage roll and a ring roll adapted to feed the material to be split, said ring roll having a plurality of ring sections capable of turning independently of each other and provided with spirally disposed indentations adapted to exert upon the material a tendency to move it longitudinally of the roll, and means for frictionally driving said ring sections.
6. A ring-roll for splitting machines, comprising a plurality of transverse sections capable of turning independently of each other, and resilient members between said sections and frictionally engaging them.
7. In a ring-roll, the combination of a plurality of independent ring-sections, and spring means for frictionally driving said rings one from another.
8. In a splitting ring, the combination of a gage roll and a ring roll adapted to feed the material to be split, said ring roll comprising a plurality of ring sections capable of turning independently of each other and each adapted to exert upon the leather a tendency to move it longitudinally of the ring roll, means for frictionally driving said ring sections one from another, and a rubber roll engaging said ring roll.
9. In a ring-roll, the combination of a plurality of independent ring-sections, means for driving one of said ring-sections, and means for frictionally driving the other ring-sections from the said first-mentioned ring-section.
10. In a ring-roll, the combination of a plurality of independent ring sections, means for driving one of said sections, and means arranged between each pair of said ring-sections for frictionally driving said ring-sections from each other.
11. In a ring-roll, the combination of a plurality of ring-sections, means for driving one of said sections, and spring means arranged between each pair of ring-sections for frictionally driving each of said ring-sections from the next adjacent ring-section.
12. In a ring-roll, the combination of a plurality of ring-sections, means for driving one of said ring-sections, and spring means for frictionally driving each of the
- ring-sections from the next adjacent ring-section.
13. In a ring-roll, the combination of a shaft, means for driving the shaft, a plurality of ring-sections loose on said shaft, and means for frictionally driving said ring-sections from said shaft.
14. In a ring-roll, the combination of a shaft, means for driving the shaft, a plurality of ring sections loose on said shaft, means for frictionally driving one of said ring-sections from the said shaft, and means for driving the other ring-sections from the said first-mentioned ring-section.
15. In a ring-roll, the combination of a shaft, means for driving said shaft, a plurality of ring-sections loose on said shaft, means for frictionally driving one of said ring-sections from the shaft, and means for frictionally driving the other ring-sections from the said first-mentioned ring-section.
16. In a ring-roll, the combination of a shaft, means for driving said shaft, a plurality of ring-sections loose on said shaft, means for driving one of said ring-sections from the shaft, and means between said ring-section and the next adjacent ring-section and between each pair of succeeding ring-sections for frictionally driving each of the ring-sections from the next adjacent ring-section.
17. In a ring roll, the combination of a shaft, a pair of spaced collars fixed on said shaft, means for rotating said shaft, a plurality of ring-sections mounted loosely on said shaft between said collars, and means for frictionally driving said ring-sections from said collars.
18. In a ring roll, the combination with a plurality of ring-sections, of means for driving said ring-sections one from the other comprising a friction member adapted to be interposed between two adjacent ring-sections and including a pair of circumferentially connected spaced and parallel spring rings.
19. In a ring-roll, the combination with a plurality of ring-sections, of means for driving said ring-sections one from the other comprising a friction ring adapted to be interposed between two adjacent ring-sections and having an interior circumferential groove forming two integral, spaced and parallel rings.
20. In a splitting machine, the combination of a gage roll and a ring roll adapted to feed the material to be split, said ring roll having a plurality of ring sections capable of turning independently of each other and provided with spiral grooves adapted to exert upon the material a tendency to move it longitudinally of the roll, and means for frictionally driving said ring sections.
21. In a splitting machine, the combination of a gage roll and a ring roll adapted

- to feed the material to be split, said ring roll comprising a plurality of ring sections capable of yielding transversely of the ring roll independent of each other and each 5 adapted to exert upon the leather a tendency to move it longitudinally of the ring roll, means for frictionally driving said ring sections one from another, and a rubber roll engaging said ring roll.
- 10 22. In a splitting machine, a roll arranged and adapted to engage the material to be split and feed it through the machine, said roll being transversely divided to form ring sections capable of turning independently 15 and said ring sections provided with means for exerting upon the material a tendency to move it longitudinally of the roll, and means for frictionally driving said ring sections.
- 20 23. In a splitting machine, a roll arranged and adapted to engage the material to be split and feed it through the machine, said roll being transversely divided to form ring sections capable of turning independently 25 and said ring sections provided with spirally
- disposed surface distortions adapted to exert upon the material a tendency to move it longitudinally of the roll, and means for frictionally driving said ring sections.
24. In a splitting machine, a roll arranged 30 and adapted to engage the material to be split and feed it through the machine, said roll being transversely divided to form ring sections capable of turning independently and said ring sections provided with spirally 35 disposed indentations adapted to exert upon the material a tendency to move it longitudinally of the roll, and means for frictionally driving said ring sections.
25. In a splitting machine, a roll ar- 40 ranged and adapted to engage the material to be split and feed it through the machine, said roll being transversely divided to form ring sections capable of turning independently 45 and said ring sections provided with spiral grooves adapted to exert upon the material a tendency to move it longitudinally of the roll, and means for frictionally driving said ring sections.

JOSEPH A. MEYER.
